(57) **CLAIM**

I claim the ornamental design for the ski goggles, as shown and described.

DESCRIPTION

FIG. 1 is a prospective view of the ski goggles showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The shade lines in the Figures show contour and not surface ornamentation.

The broken lines in the drawings show unclaimed portions of the ski goggles and form no part of the claimed design.

(Continued)

The stippled shading in the drawing disclosure represents a contrast in appearance between stippled and non-stippled areas, not surface ornamentation, and forms no part of the claim.
